THREAD CORES

Charles K. Dunlap, Hartsville, S. C., assignor to
 Sonoco Products Company, Hartsville, S. C., a
 corporation of South Carolina

Application March 8, 1937, Serial No. 129,763

2 Claims. (Cl. 242—119)

The present invention relates to cores for supporting packages of thread or yarn in the textile industry and particularly to tubular paper cores for supporting such packages while being subjected to the action of dye liquids in dyeing processes.

The advantages of the paper tube or thread core over cores of this type fabricated of other materials are substantial, the paper core being lighter in weight than metal or wooden cores, rugged and much less costly. It is desirable to provide, in the fabrication of paper cores of this type, as well as in the fabrication of cores or tubes made of other materials, some means whereby the dye liquid made use of in the dyeing process may be brought into intimate contact in sufficient quantity with the inner convolutions of the thread package to ensure that these inner convolutions are adequately dyed. Where the inner windings of thread lie upon a cylindrical thread receiving surface of a supporting core, and the dye liquid is forced outwardly through the walls of the core through a plurality of spaced apertures, those portions of the thread package which lie next to the core and between the perforations therein are frequently found to be of a different shade than the remainder of the package because having less contact with the dye liquid. Various ways have been suggested by means of which the dye liquid may be caused to flow along the thread receiving surface of the core and to thereby reach all portions of the inner windings of thread and the present invention has for its principal object the provision of a core having such a means incorporated therewith. The novel thread core hereinafter to be described in detail, however, is a departure from prior practice in that the thread receiving surface is spaced outwardly from the body of the core and may be said to comprise a large number of spaced thread receiving surfaces of small size, the spaces intermediate such surfaces readily permitting flow of dye liquid in streams parallel to the body of the core so as to reach all portions of the inner surface of the thread package. While the novel thread core may be formed in various ways I prefer to fabricate it in the manner hereinafter specified so that the finished core is substantially as illustrated in the accompanying drawing. It will be appreciated by one skilled in the art, however, that the form of invention which is set forth by way of example, while a preferred form, may be modified in minor respects without departure from the invention, and that the process of manufacture may likewise be

changed to suit the convenience of manufacture.

In the drawing:

Figure 1 is a principal view of a blank from which the novel paper core is made;

Figure 2 is a side elevation of a core, formed from the blank of Figure 1, prior to the formation of perforations therein;

Figure 3 shows in side elevation the core in Figure 2 but fully perforated, the outline of a thread package mounted on such core being diagrammatically indicated in chain lines;

Figure 4 is a side elevation of portion of the score on a larger scale; and

Figure 5 is a section on line 5—5 of Figure 4.

The blank from which the tubular core is fabricated comprises a rectangular sheet of paper, indicated at 10 in the drawing. This paper may be of any suitable grade and for the purpose of economy in manufacture the cheaper grades are used, especially grades of paper which may be deeply or heavily embossed without excessive breakage of the fiber or rupture of the sheet. One end of the sheet, indicated at 11, is subjected to the action of embossing means, this end being either passed between embossing rolls or pressed between flat embossing dies, as found most convenient. In the embossing operation to which this end of the sheet 11 is subjected, a plurality of ridges 12 are raised or struck upwardly from the surface of the sheet, these ridges 12 being preferably disposed in parallel rolls, as shown, which rolls extend transversely of the sheet. The individual ridges are relatively short and are longitudinally spaced apart, slight gaps being left by the adjacent ends of adjacent ridges. The ridges of alternate rows are staggered with respect to one another, the gaps between ridges over one row lying opposite the ridges of adjacent rows to either side thereof, also as shown in Figure 1.

After the blank is embossed in the manner just described it is wound into the form of a tube by any customary and usual winding operation upon a mandrel, the blank being so wound, however, that the embossed end 11 thereof is the last to pass on to the mandrel and also in such manner that the ridges 12 previously formed project radially outwardly from the tube or core thus formed. It will be appreciated, of course, that prior to winding the tube on the mandrel the blank is coated with a suitable adhesive so that the various plies or convolutions of the finished tube are, after the adhesive has set or hardened, securely attached to each other.

A tube formed in the manner just described is

illustrated in Figure 2. This tube is then perforated by means of any suitable perforating apparatus, a plurality of apertures such as indicated at 13 being formed in the wall thereof through which apertures dye liquid may be passed outwardly from the interior of the tube when the tube is in use as a supporting core for a thread package in a dyeing operation. The perforations 13 may be formed in the tube either before or after the adhesive used has completely dried and preferably are disposed equidistantly over the surface of the tube as indicated in Figure 3. It will be appreciated that the tube as thus formed will not stand up under the action of the dye liquid unless treated, previously to its use, with some hardening solution, and it will be understood that the paper tubes are so treated prior to actual use. The nature of the hardening solution, of which there are a number, forms no portion of the present invention and hence the hardening process and the materials used therein need not be described.

After hardening the tube is ready for use and a thread package may be wound thereon in any of the usual winding machines. From an inspection of Figure 5 it will be perceived that the windings of thread which are first applied to the tube will not contact with the cylindrical outer surface thereof but will, on the other hand, contact only with the rounded outer surfaces of the ridges 12, bridging the spaces between these ridges, and hence being held in spaced relationship to the cylindrical outer surface of the tube. The thread receiving surface of the tube, as a matter of fact, comprises a multiplicity of relatively small thread receiving surfaces instead of a substantially continuous surface, the outer rounded faces of the ridges 12, taken together, comprising the thread receiving surface of the tube or core.

When in use as a supporting core for a thread package such as indicated diagrammatically at 14 in Figures 3 and 5, dye liquid is introduced under light pressure into the interior of the tube and flows outwardly through the many ports or apertures 13. An outflowing stream of dye liquid passing through any one of the apertures 13 does not come immediately into contact with the inner windings of thread but on the other hand is discharged into a space intermediate the cylindrical surface of the tube and the innermost thread windings, and is free to flow through this space in all directions, thus having access to all

areas of the inner surface of the thread package. While it is true of course that the innermost thread windings contact with the rounded outer surfaces of the ridges 12 the area of contact between the ridges and thread windings is comparatively small and the dye liquid readily impregnates the portions of the thread winding which actually contact with the supporting ridges so that it may be said that all areas of the inner surface of the thread package are equally subjected to the action of the dye liquid and uniform dyeing of the package results.

The exact shape and arrangement of the outwardly projecting ridges may be varied as desired but in every instance the ridges or projections should function to maintain the inner thread windings out of substantial contact with the cylindrical surface of the tube intermediate the ridges or, in other words, whatever the form of the ridges, they should function as spacing elements, supporting outwardly of the tube the inner windings of thread which would otherwise contact with and lie upon its cylindrical surface.

Having thus described the invention, what is claimed as new and desired to be secured by Letters Patent is:

1. A paper core for supporting a thread package during a dyeing operation comprising a tube having a plurality of convolutions secured together and having a plurality of perforations formed in the wall thereof for the passage of dye liquid, portions of the outer convolution of the tube being outwardly deflected to provide circumferentially spaced longitudinally extending ridges upon which the inner windings of a thread package may rest and be supported, the remaining portions of the outer convolution, intermediate said ridges, resting against and being supported by the next inner convolution of the tube.

2. A paper core for supporting a thread package during a dyeing operation comprising a tube having a plurality of convolutions secured together and having a plurality of perforations formed in the wall thereof for the passage of dye liquid, portions of the outer convolution of the tube being outwardly deflected to provide circumferentially spaced longitudinally extending ridges disposed in longitudinally extending rows, the ridges of each row being separated by gaps for the circumferential flow of liquid, and the gaps of one row being intermediate the ridges of adjacent rows.

CHARLES K. DUNLAP.
